CHARLES M. PROCTOR, OF DETROIT, MICHIGAN, ASSIGNOR TO SECURITY TRUST COMPANY, OF DETROIT, MICHIGAN, RECEIVER OF P. R. MANUFACTURING COMPANY, OF DETROIT, MICHIGAN, A CORPORATION OF MICHIGAN.

CARBON-CONTACT HOLDER.

1,190,190.

Specification of Letters Patent.

Patented July 4, 1916.

Application filed March 16, 1914. Serial No. 824,908.

To all whom it may concern:

Be it known that I, CHARLES M. PROCTOR, who am a citizen of the United States, residing at Detroit, county of Wayne, State of Michigan, have invented a certain new and useful Improvement in Carbon-Contact Holders, and declare the following to be a full, clear, and exact description of the same, such as will enable others skilled in the art 10 to which it pertains to make and use the same, reference being had to the accompanying drawings, which form a part of this specification.

This invention relates to carbon terminals 15 for the armature springs of electric bells and the like, and has for its object an improved holding clip, by means of which the easily worn out carbon contact button is firmly and yet renewably held in place on the tip of the 20 spring.

In the drawings:—Figure 1 is a perspective of the end of the armature spring with the clip and carbon contact button attached. Fig. 2 is a similar perspective of a slightly 25 modified form. Figs. 3 and 4 are side elevations partly in section of the devices illustrated in Figs. 1 and 2.

A indicates the armature spring whose end is slotted as at B for the engagement 30 therethrough of the pointed or hooked tip C of the clip member D, whose center portion is apertured for the engagement therethrough of the head of the carbon button E, which is preferably, though not necessarily, 35 partially anchored with respect to the armature spring A, by means of the stud F. The end of the clip member opposite to the hooked spring-engaging end is apertured for the engagement therethrough of the screw 40 G, which engages through a complementary located and threaded aperture H, in the spring. When the button E has been placed on the spring and caused to engage through the hole in the clip D, the screw G 45 is driven as far into and through the armature spring as is necessary to tightly draw the clip over the slug E, thereby holding it in place.

In the modified form illustrated in Figs. 2 and 4, a pivoted pin J is provided for that portion of the clip L intermediate the apertured end which engages the carbon button or slug E and the end carrying the screw K; in this form the screw K, instead of being driven into and through the body or 50 mass of the armature spring to effect the drawing of the clip over the carbon slug, is actuated in the reverse direction to cause a raising of its end of the clip, with respect to the armature spring, and a consequent 55 downward tilting of the slug-engaging end of the clip.

What I claim is:—

1. In combination with an armature spring, a clip member fulcrumed in spaced 60 relation to one face thereof, a carbon button interposed between said armature spring and said clip member, and engaging partially through an aperture in said clip member, and a screw member operatively correlating said armature spring and the other end of the clip member from that engaged by 65 said carbon button, whereby the button is held in position on said armature spring with the desired degree of pressure. 70

2. In combination with an armature spring, an apertured clip member fulcrumed thereon, a carbon button resting upon said armature spring and engaging through the apertured portion of the clip member, and 75 an adjusting screw engaging the free end of the clip member and the armature spring, whereby that portion of the clip member engaging the carbon button may be forced toward or away from the armature spring, 80 thereby anchoring in position or releasing 85 the button accordingly.

In testimony whereof, I sign this specification in the presence of two witnesses.

CHARLES M. PROCTOR.
